TOY CLAMSHELL BUCKET

Oscar P. Erhardt, West Haven, Conn., assignor to
 The A. C. Gilbert Company, New Haven, Conn.,
 a corporation of Maryland

Application January 22, 1942, Serial No. 427,685.

19 Claims. (Cl. 37—184)

This invention relates to toys which are imitative of outdoor industrial apparatus such as sectional buckets swung from a derrick, traveling crane, or the like for handling and transferring materials in miniature quantities in a manner to simulate the industrial operations of shoveling, dredging etc. The present improvements particularly concern a clamshell type of bucket which scoops up its load of material by forcing jaw-like bucket sections together thereunder and discharges such load merely by permitting said sections to open and let the contents fall out.

One object of the invention is to provide a toy clamshell bucket that does not require actuation of its opening and closing mechanism by means of flexible haulage rigging such as trailing ropes and cables. These require more weight to react against than is possessed by a light toy bucket and would impede the gravity effected movements of the latter.

Another object is to incorporate within the unitary structure of a toy clamshell bucket suspended from a carrying cable an electromagnet whose successive electrical energization and deenergization will cause jaw-like sections of the bucket first to swing closed responsive to the force exerted by the electromagnet and later to swing open again merely under the action of gravity or the weight of the contained load material.

A further object is to equip such a toy clamshell bucket with an electromagnet in the form of a solenoid having a vertical axis and a vertically reciprocative plunger connected to cause simultaneous swinging movements of both of the jaw-like bucket sections.

A further object is to make the solenoid fast to the suspension head of the bucket unit while the aforementioned plunger serves as a lengthwise reciprocative connecting rod acting alternately to raise and to permit lowering of a horizontal wrist pin carried thereby and which serves to couple pivotally together relatively swingable sections of the clamshell bucket.

A still further object is pivotally to anchor and maintain the top edges of the swingable bucket sections at a common restricted range of levels in relation to the suspension head of the unit so that raising and lowering of the aforesaid wrist pin will operate to swing the jaw-like bucket sections open and closed.

Another object is to make the bucket sections and the suspension head of simple and light weight sheet metal parts thereby to reduce the weight of the unit and the consequent load burden on light duty toy motors which may be em-

ployed to motivate it and also to decrease the cost of production.

The above stated objects are attained by the constructions and modes of operation hereinafter described and constituting one successful embodiment of the invention. The following description has reference to the accompanying drawing wherein:

Fig. 1 is an isometric view drawn on an enlarged scale showing a toy clamshell bucket embodying the present improvements with the bucket sections in open position.

Fig. 2 is an end view of the same bucket drawn on a reduced scale indicating a size thereof suitable for toy use.

Fig. 3 is a side view looking from the right at Fig. 2.

Fig. 4 is a view like Fig. 2 showing the bucket sections in closed position.

Fig. 5 is a fragmentary view drawn on an enlarged scale taken in section on the plane 5—5 in Fig. 2, looking in the direction of the arrows.

Fig. 6 is a fragmentary view on the same scale as Fig. 5 taken in section on the plane 6—6 in Fig. 2, looking in the direction of the arrows.

Fig. 7 is a fragmentary view taken in section on the plane 7—7 in Fig. 6, looking in the direction of the arrows.

Fig. 8 is a fragmentary plan view taken in section on the plane 8—8 in Fig. 7.

While the working parts of this improved toy bucket may have a variety of constructions embodying the principles of the improvements, the embodiment herein chosen to illustrate the invention involves a suspension head 10 comprising a sheet of metal with turned down end flanges 11 containing anchorage holes 12 in each of which holes is loosely hooked the top end 13 of one of the four stiff suspension links 14. A round central aperture in the suspension head plate 10 is occupied by the cylindrical barrel 16 of non magnetic material forming part of a solenoid structure designated as a whole by 17 and further including a top end washer 18, a bottom end washer 19, and a paper wrapping 21, all being preferably of electrical insulative material. The turned-over ends of the barrel 16, as clearly shown in Fig. 5, firmly hold together in an axial direction the insulative parts 18, 19 and 21, and hold these parts rigidly in fixed relation to the suspension head 10. A tight plug 22 is fixed in the top end of barrel 16 with its head overlapping the end of the latter and provided with a peaned-over projection 29 which holds fixed to plug 22

a U-shaped shackle-block 15 between whose up-

standing arms a sheave 30 is rotatably supported on pivot spindle 44, journaled in the spaced arms of the shackle block. A coupling loop 24 has its ends secured to the respective ends of spindle 44 which project outside of the shackle block so that loop 24 is free to swing relative to shackle block 15 while sheave 30 is free to rotate relative both to the spindle 44 and to the shackle block 15. If desired, spindle 44 may comprise a tubular rivet, eyelet or the like. Thus the clam-shell bucket as a unit may be suspended by means of a flexible cord (not shown) passing around the sheave or by a hoist cable or chain, as 40, herein-after described.

The terminals of the winding 26 of insulated electrical conductive wire of solenoid 17 are connected respectively to long flexible leads 27 and 28 which may extend from the bucket to a remote source of electric current for energizing and deenergizing the solenoid while leaving the bucket free to be transported in all directions to any distance within its designed range of working movements.

Vertically reciprocative within the core chamber of solenoid barrel 16 is a plunger rod 29 whose upper portion at least is of readily magnetizable material and whose projecting lower end, as best shown in Fig. 6, is bored crosswise to receive and provide snug pivotal fit for the horizontal wrist pin 31 extending at right angles thereto. Each of the opposite ends of wrist pin 31 has pivotal engagement with two overlapping end walls 32 of two relatively swingable jaw-like bucket sections 33 and 34. The top edges of these sections which are most remote from wrist pin 31 are provided with anchorage holes 36 in which respectively are loosely hooked the bottom ends 37 of the suspension links 14. It will be noted that the loops 37 are disposed in quarter twisted relation to loops 13 whereby limited freedom for the bucket sections to swing in universal directions is provided.

A flat thrust washer 38 separates one flattened end of the wrist pin 31 from the adjacent end walls 32 of the bucket sections while a check tab 39 of inverted U-shape hangs on the relatively movable top edges of the opposite overlapping end walls 32 of the bucket sections and contains a vertically elongated slot 41 which is occupied by the opposite terminal portion of the wrist pin 31 between the other flattened end of the latter and said overlapping end walls 32, thereby to serve as a stop limiting the degree of opening movement of the two bucket sections 33 and 34. Spacer collars 42 and 43 serve to maintain the solenoid plunger 29 central of the wrist pin 31.

In use the loop 24 and thereby the entire clam-shell bucket of Fig. 1 as a unit is coupled to and suspended at the end of hoist cable 40 that may depend in usual manner from a pulley on a swinging derrick, traveling crane, or the like, whereby the bucket may be transported to a point over any desired area within the range of movement of the derrick arm or crane and be raised and lowered at will by means of such cable. The flexible electric cord 25 is understood to connect with some stationary remote source of current supply and to be loose and long enough to trail the toy bucket without offering resistance to its movements or being used in any way to actuate the bucket parts mechanically.

Thus the bucket may be maneuvered into a position above, say, a pile of sand while its jaws

32 and 35 remain swung open as shown in Figs. 1 and 2. Normally these jaws or complemental bucket sections are thus held open by the combined weight of the free plunger 29, the wrist pin 31, of the spacer collars 42, 43 and of the bucket sections themselves. In this condition the cable supported loop 24 can suddenly be lowered permitting the bucket to drop abruptly upon the top of a pile of sand or other dislodgable material. Now by means of a remotely located electric switch (not shown), the solenoid winding 26 can be electrically energized through wires 27, 28 thus creating a strong magnetic field around the core sleeve 16 which will serve to draw the plunger 29 smartly upward and raise the wrist pin 31 a corresponding distance. This electromagnetic action causes the bucket jaws 32, 35 to swing toward each other to their positions shown in Fig. 4 whereupon they bite into and under the sand or other loose load material so that the bucket jaws cooperate automatically to scoop up into the resulting closed bucket a load of such sand or other loose material.

As long as the solenoid remains electrically energized the bucket jaws 32 and 35 will remain closed and will retain the contained load of material so that the cable 40 of the crane or derrick arm can then lift the bucket and its load to any desired elevation and transport it to a position over any location, within the range of action of the toy, in which it may be desired to dump the load. Dumping is effected by merely cutting off the supply of current to the solenoid through appropriate manipulation of the aforementioned remote control switch. Thereupon plunger 29 will cease to be attracted upwardly and with its associated parts will drop to the position shown in Figs. 1, 2 and 5 assisted by the weight of the load acting upon the swingable bucket sections themselves. This causes the bucket jaws suddenly to swing apart and thus discharge the bucket contained load of sand so that the sand drops straight downward. My improved bucket is thus operated through a remote source of control and preferably electrically in a way to make unnecessary any supplemental cables running to the bucket sections for mechanically actuating them.

In certain of the appended claims the wrist pin 31 and equivalents therefor is termed a hinge element and it will be seen to establish a common axis about which the bucket sections are swingably movable at the same time that they swing about their points of suspension from the links 14. It will further be understood that the engagement of the looped ends of these links with the anchorage holes 12 and 36 is loose to a degree permitting dangling or substantial weaving or twisting action of the bucket sections in unison and in universal directions relative to the suspension head. In other words the above said common axis of wrist pin 31 is free to swing relative to suspension head 10 within limits in all directions in a horizontal plane. This prevents binding in action and avoids the necessity of nice fits and enables the lips 33, 34 of the bucket sections to better individually adjust themselves and grab into the loose material being scooped up as the bucket sections bite together. There may also be a generous degree of looseness in the fit of plunger 29 within the solenoid core sleeve 16.

Many modifications of detail and structure will be suggested to those skilled in the art by the disclosure hereof and the appended claims refer to

and are intended to be inclusive of all fair substitutes and equivalents which come within their terms.

I claim:

1. Toy load digging and hoisting apparatus including in combination with a toy lifting cable, an automatic toy clam-shell bucket embodying an uppermost crosshead attached to said cable, jaw-like bucket sections pivotally coupled together having mating lips, separate suspension means connecting said bucket sections respectively to said crosshead, an electromagnet attached fixedly to and depending from said crosshead, and a movable armature disposed constantly within range of attraction of said electromagnet thereby to perform movement in response to electrical energization of the latter and connected to said bucket sections in such manner that said movement of the armature impels said bucket sections in directions to move said bucket lips toward each other thereby to close the bucket.

2. Toy load digging and hoisting apparatus including in combination with a toy lifting cable, an automatic toy clam-shell bucket embodying an uppermost crosshead attached to said cable, jaw-like bucket sections pivotally coupled together having mating lips, links suspending said bucket sections and separately coupled pivotally to said crosshead structure, an electromagnet attached fixedly to and depending from said crosshead, and a movable armature disposed constantly within range of attraction of said electromagnet thereby to perform movement in response to electrical energization of the latter and connected to said bucket sections in such manner that said movement of the armature impels said bucket sections in directions to move said bucket lips toward each other thereby to close the bucket.

3. An electrically controllable self opening and closing toy clamshell bucket including the combination of, an uppermost crosshead structure adapted for attachment to a toy lifting cable, a vertically elongated hollow solenoid core having its upper end fixed to said crosshead structure and depending therefrom, a solenoid winding of electrical conductive wire around said core beneath said crosshead structure, jaw-like bucket sections pivotally coupled together having mating lips, separate links suspendedly connecting said bucket sections respectively to said crosshead structure, a magnet plunger attractable by electrical energization of said winding thereby to move upward within said hollow core, and connections between said bucket sections and said magnet plunger constructed and arranged to cause swinging movements of the bucket sections toward each other when said plunger moves upward in said core thereby to enable said electromagnetic force of the solenoid to close the bucket.

4. A self-operating toy clamshell bucket including the combination of, an uppermost crosshead structure adapted for attachment to a toy lifting cable, a vertically elongated hollow solenoid core fixed to and depending from said crosshead structure, an electrical solenoid winding around said core, jaw-like bucket sections pivotally coupled together, rigid links suspendedly connecting said bucket sections respectively to said crosshead structure, and a magnetizable plunger operatively independent of said cable attractable by the electrical energization of said winding to move upward within said core, and connections between said bucket sections and said plunger

constructed and arranged to cause said bucket sections to swing relatively when said plunger moves upward in said core.

5. An electrically controllable self opening and closing clamshell bucket including the combination of, jaw-like bucket sections pivotally coupled together having mating lips, an uppermost crosshead structure above said bucket sections adapted for attachment to a lifting cable, links suspending said bucket sections and separately coupled pivotally to said crosshead structure, a vertically elongated hollow solenoid core fixed at its upper end to said crosshead structure and depending therefrom, a solenoid winding of electrical conductive wire around said core beneath said crosshead structure, a solenoid plunger attractable by electrical energization of said winding and thereby caused to move upward in said core, and connections between said plunger and said bucket sections so constructed and arranged that upward movement of said plunger impels said bucket sections in directions to swing said bucket lips toward each other thereby to close the bucket.

25 6. Toy load digging and hoisting apparatus including in combination with a lifting cable, a toy clamshell bucket embodying a horizontally extending head plate attached to said cable, stiff links separately and swingably coupled to said head plate at horizontally spaced points, jaw-like bucket sections coupled to said links for relative swinging movement toward and away from closed relationship, a hinge element pivotally connecting said bucket sections and constraining them to relative swinging movement about a common axis, a magnetic plunger connected to said hinge element, a vertical hollow tubular core depending fixedly from said head plate constraining said plunger to a path of longitudinal movement relative to said head plate, and means to reciprocate said plunger along said path for causing said relative swinging movement of said bucket sections including a solenoid electrical winding surrounding said core beneath said head plate between said links and above said bucket sections.

45 7. Toy load digging and hoisting apparatus as defined in claim 6, in which the said links are four in number and are coupled both to the said head plate and to the said bucket sections in a manner permitting limited swinging movement of the said common axis in universal directions relative to said head plate.

50 8. Toy load digging and hoisting apparatus as defined in claim 6, in which the said links are four in number and each of said links has looped ends disposed in quarter twisted relation at respectively opposite ends of the link end engaging said head plate and said bucket sections with sufficient looseness to permit limited swinging movement of the said common axis in universal directions relative to said head plate.

55 9. Toy load digging and hoisting apparatus including in combination with a lifting cable, a toy clamshell bucket embodying a horizontal plate-like suspension head attached to said cable having laterally spaced turned down ears containing spaced anchorage holes, at least four links bent to form top loops at their upper ends hooked into said holes respectively with a dangling loose bit and bent to form bottom loops at their lower ends, jaw-like bucket sections having spaced anchorage holes into which said bottom loops hook with a dangling loose bit, a hinge element pivotally connecting said bucket sections for rela-

tive swinging movement about a common axis, a vertical rod connected to said hinge element, a guideway constraining said rod to a path of longitudinal movement relative to said head, and means to reciprocate said rod along said path in a manner to cause said relative swinging movement of said bucket sections while the latter are suspended from said links.

10. A toy clamshell bucket embodying in combination, a head adapted to dangle from a hoist cable, a solenoid depending centrally and fixedly from said head having a normally vertical axis, a vertical plunger rod movable upward and downward in the magnetic field of said solenoid, a horizontal hinge pin lodged tightly in a cross hole extending crosswise the lower end of said rod, complementary jaw-like bucket sections having overlapping flanges pivotally engaging each end of said pivot pin, and means to suspend said bucket sections swingingly from said head.

11. A toy clamshell bucket as defined in claim 10, together with tubular spacer collars carried by the said wrist pin between the said plunger rod and the said overlapping portions of the said bucket sections for affording aligning thrust to centralize said bucket sections in lateral relation to the said solenoid and also weighting downward said hinged portions of the bucket sections.

12. A toy clamshell bucket embodying in combination, a solenoid spool equipped at one end with a loop for suspending the same in a vertical position from a hoist cable, a head plate overlying and fixed to the top end of said spool presenting four spaced anchorage lugs at points blanking the top end of said spool, four links dangling from said anchorage lugs in a manner to be swingable in all directions alongside said spool, complementary jaw-like bucket sections swung loosely from said links having mating lips, and actuating mechanism connected to said bucket sections constructed and arranged to be motivated by said solenoid in a manner to swing said sections relative to said spool in a manner to cause said lips to meet.

13. Toy load digging and hoisting apparatus including in combination with a lifting cable, a toy clamshell bucket embodying a suspension head attached to said cable, links swingably coupled to said head at laterally spaced anchorage points, jaw-like bucket sections swung from said links, a hinge element pivotally connecting said bucket sections and permitting relative swinging movement of the latter about a common axis to closed relationship, a magnetically attractive plunger rod connected to said hinge element, a vertical spool-like structure having its top end secured to a central portion of said head flanked by said anchorage points, said structure containing a vertically elongated core chamber constraining said rod to endwise sliding movement therewithin, and a winding of solenoid wire on said spool-like structure operative to attract said rod magnetically into said chamber for causing

relative swinging movement of said bucket sections.

14. Toy load digging and hoisting apparatus including in combination with a lifting cable, 10 a toy clamshell bucket embodying a suspension head attached to said cable, links swingably coupled to said head at laterally spaced anchorage points, jaw-like bucket sections swung from said links, a bodily liftable hinge element pivotally connecting said bucket sections in a manner when lifted to cause relative swinging movement of the latter about a common axis to closed relationship, a plunger rod connected to said hinge element in a manner to lift the latter bodily when magnetically attracted, 15 a vertical spool-like structure having its top end fixedly secured to a central portion of said head flanked by said anchorage points, said structure containing a vertically elongated core chamber constraining said rod to endwise sliding movement therewithin, and a winding of solenoid wire on said spool-like structure operative to attract said rod magnetically into said chamber thereby to cause said bucket sections to close.

20 16. A toy clamshell bucket embodying in combination, a head adapted to dangle from a hoist cable, a solenoid fixed to and depending centrally from said head having a normally vertical axis, a vertical plunger rod movable upward and downward in the magnetic field of said solenoid, a horizontal wrist pin carried by the lower end of said rod, complementary jaw-like bucket sections having portions thereof hinged on said wrist pin, and means swingably to suspend said bucket sections 25 from said head, together with a stop engaging said hinged portions of said bucket sections and engaged by said wrist pin in a manner to limit the relative swinging movement of said bucket sections about said wrist pin in at least one direction.

30 17. A toy clamshell bucket embodying in combination, a solenoid spool adapted to be suspended with its axis vertically disposed, a shackle block fixed on the top of said spool, a sheave pivotally 35 mounted on said shackle block, a loop pivotally mounted on and straddling said shackle block, a head structure fixed on the top of said spool providing spaced anchorage lugs, links depending from said lugs, and cooperative bucket sections 40 pivotally supported by said links.

45 18. A toy clamshell bucket as defined in claim 16 in which the said sheave and the said loop are pivotally mounted in coaxial relation.

50 19. A toy clamshell bucket as defined in claim 16, together with a pivot spindle journaled in the said shackle block and extending through both the said sheave and the said loop.

55 20. A toy clamshell bucket as defined in claim 16, in which the said shackle block is U-shaped and includes laterally spaced upright arms flanking respectively opposite sides of the said sheave and flanked respectively by opposite ends of the said loop.
